UNITED STATES PATENT OFFICE.

EDWARD J. KING AND THOMAS R. KENNEDY, OF ROCHESTER, NEW YORK,
ASSIGNORS TO THE CO-OPERATIVE FOUNDRY COMPANY, OF SAME PLACE.

DESIGN FOR A COOKING-STOVE.

SPECIFICATION forming part of Design No. 30,742, dated May 9, 1899.

Application filed March 22, 1899. Serial No. 710,102. Term of patent 7 years.

To all whom it may concern:

Be it known that we, EDWARD J. KING and THOMAS R. KENNEDY, citizens of the United States, residing at Rochester, Monroe county, New York State, have invented and produced a new and original Design for a Cooking-Stove, of which the following is a specification, reference being had to the accompanying drawing, forming a part thereof.

10 The drawing is a perspective view illustrating a stove or range embodying our present design.

The leading feature of the design is the shape and ornamentation of the stove as a whole and of the separate parts thereof, as will be more particularly described in the following specification.

15 A indicates the base of the stove, having the legs *a* and also having scroll ornamentation *b* at the center of the front, extending in opposite directions toward the corners, terminating in the large scrolls *c*. The corners of the base are decorated with the ornamentation *d*, extending down upon the upper portion of the legs. Upon the top of the base is the plain band *e*, extending around the stove.

20 Arranged upon the end of the stove is the hearth *F*, having the smooth depending rim *g*, curving upward at the corner of the stove and extending at the side of the body, as at

f, and below this is the ash-pit section *G*, inclined at the front and having an ornamentation *i*. Above the hearth is the front ash-pit door *J*, rounded upon the sides and having the ornamentation *j* across the top, 35 and below this is the draft-damper *k* and the ornamentation *l*. The side ash-pit door *K* is ornamented with the scroll ornamentation *k'*.

M indicates the oven-door, having its edges rounded and provided at the center with the 40 panel *m*, embellished about its edges with a border of scrollwork *n*. Outside of the panel the door *M* is also decorated with conventional scrollwork *N* in bold relief, extending over the rounded edges of the door.

45 P indicates a reservoir extension forming the panels *p*, ornamented with bold relief scrollwork *q*.

R indicates the oven-shelf, located beneath the oven-door, having the rounded edge *s* and 50 the flat surface ornamentation, as shown.

We claim as our design—

The design for a stove, substantially as herein shown and described.

EDWARD J. KING.
THOMAS R. KENNEDY.
